Inventor,
W. L. Barrett, by
G. C. Kennedy,
Attorney.

UNITED STATES PATENT OFFICE.

WILLIAM L. BARRETT, OF WATERLOO, IOWA.

HAND-CULTIVATOR.

1,370,180.

Specification of Letters Patent.

Patented Mar. 1, 1921.

Application filed June 19, 1920. Serial No. 390,200.

To all whom it may concern:

Be it known that I, WILLIAM L. BARRETT, a citizen of the United States of America, and a resident of Waterloo, Blackhawk 5 county, Iowa, have invented certain new and useful Improvements in Hand-Cultivators, of which the following is a specification.

My invention relates to improvements in hand cultivators, and the object of my improvement is to supply a tool-carrying hand cultivator with means for adjusting the relative positions of the tools both vertically and laterally, as also to permit interchange thereof with other tools.

15 This object I have attained by the means which are hereinafter described and claimed, and which are illustrated in the accompanying drawings, in which Figure 1 is a side elevation, and Fig. 2 a plan view of my improved hand cultivator, in both a part of the handle being broken away. Fig. 3 is a plan view of a modification of said device.

Similar numerals of reference denote similar parts throughout the several views.

25 The numeral 1 denotes an elongated handle on one end of which is fixed a socket 2 provided with an alined projection 3, the latter preferably discoidal, centrally transversely orificed, and provided on one side face with numerous radially-disposed detents. Upon this projection or clutch-member is fitted a mating clutch-member 4, whose like radial teeth 5 fit between and engage the detents on the member 3, and this 35 member 4 has a registering central orifice, a bolt 6 traversing the said orifices, and a wing-nut 7 securing said members together in such a relative relation that the member 4 is adjusted on the member 3 as desired.

40 The member 4 has a forwardly directed integral projection formed into a receiving-head 8, the latter being elongated transversely and being hollowed longitudinally to receive the middle bar or portion of an 45 elastic forked member 10, the forks whereof serve as supporting shanks for tools such as blades 12 secured removably on the downwardly curved extremities thereof. These shanks may be partially twisted at 11 to 50 have inwardly-directed parts which stiffen them. The forked body 10 has its medial part which is seated in the hollow of the head 8 secured thereto by means of bolts 9.

As the forks of the body 10 are resilient, the tools 12 may be adjusted laterally to and from each other by the following-described adjustable connecting-means. In each web 55 11 is an orifice 14 receiving the hooked outer end of a threaded rod-part 15, the parts 15 being alined and their opposed threaded ends joined adjustably by means of a turn-buckle 16. The forks 10 will elastically yield sufficiently to permit this adjustment, while the forks may have their angle of inclination changed by use of the above-mentioned 60 adjustable clutch-members 3 and 4. The tools or blades 12 are secured to the forks by bolts 13, so these tools may be removed and other or different tools mounted in their place.

70 In Fig. 3, the clutch-members 3—4 are the same, but the head 17 of the projection 8 is solid, and longer, and has at each end forks 18. Tool-carrying shanks 10 are inserted between these end forks, and secured thereto 75 removably by means of bolts 19. In this modification the shanks are rigid, and the adjustment by only vertically rocking the member 4 relatively to the member 3.

Having described my invention, what 80 I claim as new, and desire to secure by Letters Patent, is:

1. In a device of the character described, a handle, a clutch-face member rigidly mounted thereon, soil-working implements, 85 and elastic connecting supporting elements between said implements and said member adjustably secured on the latter for vertical rocking adjustments.

2. In a device of the character described, 90 a handle, laterally spaced soil-working implements, and a U-shaped supporting device on whose extremities the implements are mounted, the device being mounted for vertical rocking adjustments on said handle, 95 and the members of the device being elastic, and laterally-adjustable connections between said members.

3. In a device of the character described, 100 a handle, a shank mounted thereon for vertical rocking adjustments, laterally adjustable elastic tool-carrying members mounted on said shank, and tools mounted removably on said members.

4. In a device of the character described, 105 a handle, a branched body with elastic mem-

bers spaced apart laterally, soil-working tools mounted terminally on said members removably, and an adjustable connecting-means between said members operable to vary the spread apart laterally thereof.

5. In a device of the character described, a tool-carrying device having laterally spaced elastic members, soil-working tools mounted removably on said members, said

members having stiffening-means for rendering them non-elastic vertically only, and adjustable connecting-means between said members, comprising elements connected to the members transversely and a turn-buckle connecting said elements.

Signed at Waterloo, Iowa, this 4th day of June 1920.

WILLIAM L. BARRETT.
